UNITED STATES PATENT OFFICE.

THEODORE GUILLEAUME, OF MÜLHEIM-ON-THE-RHINE, GERMANY.

ELECTRIC CABLE.

SPECIFICATION forming part of Letters Patent No. 514,925, dated February 20, 1894.

Application filed October 6, 1893. Serial No. 487,321. (No model.) Patented in France April 14, 1893, No. 220,891; in Belgium April 14, 1893, No. 104,271, and in Italy August 8, 1893, XXVII, 34,551, LXVII, 473.

To all whom it may concern:

Be it known that I, THEODORE GUILLEAUME, a subject of the German Emperor, residing at Mülheim-on-the-Rhine, in the German Empire, have invented new and useful Improvements in Electric Cables, (in respect whereof I have obtained Letters Patent in France, No. 220,891, dated April 14, 1893; in Belgium, No. 104,271, dated April 14, 1893, 5 and in Italy, XXVII, No. 34,551 and LXVII, No. 473, dated August 8, 1893, and for which I have applied for but have not obtained Letters Patent in the following countries, to wit: Great Britain, No. 7,782, under date 15 April 17, 1893; Germany, No. 6,789, under date May 6, 1893; Sweden, No. 602, under date July 22, 1893; Austria-Hungary, under date July 31, 1893; Switzerland, No. 8,187, under date October 20, 1893, and Russia, No. 11,845, 20 under date August 25, 1893,) of which the following is a specification.

This invention relates to electric cables or conductors embodying one of the principal features of my invention forming the subject 25 of Letters Patent No. 483,285, dated September 27, 1892.

In the accompanying drawings, Figure 1 is a transverse section of a cable made in accordance with the present invention and 30 adapted for use in the "three-wire" system. Fig. 2 shows a similar cable in which the component wires are of different shape. Fig. 3 represents a cable suitable for employment in the "five-wire" system; the protective 35 sheathing being utilized as the fifth conductor. In Fig. 4, the fifth conductor consists of a group of wires placed outside the exterior insulation. In Fig. 5, the fifth conductor is a single wire in the center of the cable.

40 The cables particularly described with reference to the drawings forming part of the specification to the aforesaid Letters Patent are principally intended for telephonic and telegraphic transmission.

45 The object of the present invention is to produce cables or conductors to some extent similar in character, but specially adapted for electric light service or transmission of power on the "three-wire" or the "five-wire" 50 systems, wherein the formation of air-spaces is of less practical importance; a special ad-

vantage of the present method of construction being that several conductors of unequal sectional area may be readily united to produce a compact cylindrical cable, the manufacture of cables of this class having hitherto 55 presented considerable difficulty.

According to one mode of carrying out this invention, three conductors a , a' and a^2 for use in the "three-wire" system and a body 60 of insulating material c , three-armed in transverse section, are twisted together, the several conductors lying in the respective grooves of the insulating material c , and being thus separated from one another. Each conductor a , a' or a^2 may be a strand comprising any suitable number of wires of any appropriate transverse section or sections. The insulating strip or body c and the conductors a , a' and a^2 twisted therewith are surrounded by 65 exterior insulation d , which may be protected by sheathings e and f of lead, hoop iron or other material.

In a cable adapted for use in the "five-wire" system, the two principal conductors 75 a^3 and a^4 and the two secondary conductors a^5 and a^6 may consist of strands of wire, as shown in Figs. 3, 4 and 5. In Fig. 3, the protective sheathing e serves as the fifth conductor; economy in first cost being hereby 80 attained. Or, the fifth conductor may be formed of single wires a^7 placed equidistantly around the exterior of the insulating envelope d , as represented in Fig. 4, and twisted together with the main conductors 85 and insulating material. Or, the fifth conductor may consist of a single wire a^8 arranged in the center of the cable, as illustrated in Fig. 5.

What I claim as my invention, and desire 90 to secure by Letters Patent, is—

1. For electric light service or transmission of power, a cable circular in transverse section but comprising a body of grooved insulating material irregular in transverse section, 95 and several conductors of unequal transverse section twisted together with the insulating material, each groove in the insulating material being just large enough to hold the conductor lying within the same, substantially 100 as set forth.

2. For electric light service or transmission

of power, a cable circular in transverse section but comprising a body of grooved insulating material irregular in transverse section, main and secondary conductors of unequal transverse section twisted together with the insulating material, each groove in the insulating material being just large enough to hold the conductor lying within the same, and a fifth conductor separated from the other 10 conductors by insulating material, substantially as set forth.

3. For electric light service or transmission of power, a cable circular in transverse section but comprising a body of grooved insulating material irregular in transverse sec- 15

tion, main and secondary conductors of unequal transverse section twisted together with the insulating material, each groove in the insulating material being just large enough to hold the conductor lying within the same, and a fifth conductor consisting of a series of single wires placed equidistantly around the exterior insulating envelope and twisted with the other conductors and the insulating material, substantially as set forth. 20

THEODORE GUILLEAUME.
